UNITED STATES PATENT OFFICE

AARON E. KING, OF FRESNO, CALIFORNIA

VIBRATOR DISTRIBUTING ROLL FOR PRINTING PRESSES

Application filed October 1, 1929. Serial No. 396,419.

This invention relates to printing presses, and particularly to one of the platen type such as are commonly used in job printing shops. The invention also relates to and 5 represents improvements over the commonly used means for distributing the ink to the form rollers. Such means as is now used comprises vibrator distributor rolls placed between and engaging adjacent form rolls 10 and mounted in connection with springs so that they bear down against the form rolls at all times and with a constant pressure. Such an arrangement is shown for instance in Patent No. 1,381,948 granted June 21, 1921, to 15 R. O. Vandercook. This device however is somewhat unsatisfactory for the reason that the constant pressure against the form rollers retards the free rotation of the same and tends to result in the ink being smeared 20 rather than rolled onto the type in the chase.

The object of my invention is to avoid this objectionable feature by providing a vibrator distributor roller so mounted that the form rollers may move freely and easily at all 25 times; and so that the last roller of the form roller unit to leave the type on the upward stroke, is entirely free from contact with the distributing roller, so as not to offer any resistance to the desired free rolling movement 30 of said form roller.

A further object is to provide an improved automatically functioning trip for the vibrating control member of the distributing roller unit, so that if said roller reaches the 35 end of its endwise travel before the form rollers reach the end of their travel lengthwise of the press, the distributing roller will continue to rotate instead of tending to slide and without the tendency of the distributing 40 roller shaft jumping out of its bearings, as is the case with the structure at present in use.

A further object of the invention is to provide a simple and inexpensive device and yet one which will be exceedingly effective 45 for the purpose for which it is designed.

These objects I accomplish by means of such structure and relative arrangement of parts as will fully appear by a perusal of the following specification and claims.

50 In the drawings similar characters of ref-

erence indicate corresponding parts in the several views:

Fig. 1 is a fragmentary side outline of a platen press showing the position of the distributing roller on the upstroke or oscillation of the pivoted roller frames. 55

Fig. 2 is a similar view showing the position of the distributing roller on the downstroke.

Fig. 3 is a side elevation of the distributing 60 roller unit as mounted in connection with the central form roller.

Fig. 4 is a fragmentary longitudinal section of the unit.

Fig. 5 is a cross section of the rollers showing the position of the distributing roller on the up-stroke. 65

Referring now more particularly to the characters of reference on the drawings, the numeral 1 denotes the frame of the press on 70 which the vertically disposed chase 2 and the relatively horizontal ink disc 3 are mounted. The side rails 4 are provided with the frame and extend parallel to the chase from a point substantially flush with the face of the disc as is customary. The three spaced and parallel form rollers 5 of the usual soft composition are journaled in saddles 6 which are yieldably supported by the pivoted and oscillating roller frames 7 disposed to the sides 75 of the press. The above parts are all standard in presses of this character, and in operation the frames 7 are oscillated through an arc or stroke of sufficient length to cause the rollers to travel over the face of the disc 3 80 and down the chase, and vice versa.

My improved vibrator distributing roller unit is mounted in connection with the central one of the rollers 5 and is constructed as 85 follows:

Turnable on the shaft 8 of said roller 5 between the supporting saddles 6 and the side rail engaging rollers 9, which are keyed on said shaft, are collars 10, from which short radial arms 11 project. 95

It may here be noted that the rollers 9 ordinarily provided to engage the rails are preferably removed, and special ones, arranged to have a more positive frictional grip with the rails, are provided. Slidable on the 100

arms 11, which are in the form of threaded studs, are blocks 12 adjustable along and secured in place on the studs by opposed nuts 13 thereon. These blocks support a shaft 14 extending therebetween and disposed parallel to the roller 5. The metal distributing roller 15 is turnable on the shaft 14, the blocks 12 being so adjusted that said roller firmly engages the roller 5. This roller 15 is in the form of a tube having end bushings 16 fixed thereon. One bushing turns directly on the shaft 14 while the other is tapped and engages a threaded sleeve 17 turnable on the shaft. This sleeve is yieldably held from free turning by a cross pin 18 on the shaft 14 inwardly of said sleeve which engages a notch 19 cut in the adjacent end of the latter. A compression spring 20 is disposed about the shaft 14 between the end block 12 and the adjacent end of the sleeve and bears against the latter to maintain the notch engaged with the pin. The adjacent bushing 16 has stops 21 projecting from both ends of the same and adapted to engage stops 22 fixed on the sleeve 25 at its opposite ends.

In operation it will be seen that if the form roller unit travels down the ink disc and chase the distributing roller will swing, by reason of its engagement with the central roller 5 and the direction of rotation of the latter, so that the distributing roller will project between and engage both the lowermost and central roller. It cannot then swing any further, so that it will then turn about its supporting shaft 14. Owing to the threaded engagement of the roller with the sleeve 17 such rotation causes a longitudinal or endwise movement to be imparted to the roller, so that the ink received onto the rollers 5 from the disc is distributed along the rollers. This movement of the distributing roller will continue until the form rollers reverse their direction of rotation or until the tapped bushing 16 reaches the end of its movement 45 along the sleeve in one direction or the other. The cooperating stops 21 and 22 then engage each other and the sleeve turns with the roller, since the engagement of the pin 18 with the notch 19 is then overcome. This prevents slipping of the distributing roller on the form rollers without placing any material strain on the shaft 14 such as would tend to rotate the same. The ink is thus well distributed onto the lowest form roller, as well as onto 50 the central roller, the engagement of the distributing roller with the lowest roller being aided by the weight of the former and its connected parts.

When the direction of movement of the form rollers is reversed with the reversing of the oscillating stroke of the frames 7, the distributing roller immediately swings from its engaging position with and between the lowest and central form rollers 55 to a similar position between the central

and top rollers; the ink distributing endwise movement of the distributing roll then again taking place but in the opposite direction. The lowest roller 5 is then free of the distributing roller and of any influence which might tend to retard its free rotation. This enables said roller, which is the last one to leave the type on the chase, to ink the same by a free rolling movement, as is necessary to obtain the best results; and there is no tendency for said roller to slide over the type and smear the ink, as is the case with the standard arrangement in which the distributing roller constantly bears down against the lowest form roller. 70 75 80

It will also be evident from the foregoing description that the adjacent pairs of form rollers will be engaged by the distributing roller at all times regardless of the wear of the form rollers; and that the only adjustment necessary to compensate for wear may be easily made by adjusting of the blocks 12 so that the roller 15 always engages the central roller 5 with the desired pressure. 85

It is also to be understood that while I have particularly described this arrangement for use in connection with platen presses it may also be adapted for any presses which use a similar arrangement of inking rollers. 90

From the foregoing description it will be readily seen that I have produced such a device as substantially fulfills the objects of the invention as set forth herein. 95

While this specification sets forth in detail the present and preferred construction of the device, still in practice such deviations from such detail may be resorted to as do not form a departure from the spirit of the invention, as defined by the appended claims. 100

Having thus described my invention what I claim as new and useful and desire to secure by Letters Patent is:

1. An ink distributing attachment for a printing press having three form rollers, and means for moving said rollers as a unit in opposite directions alternately; comprising a distributing roller, and means mounting said roller in place relative to the form rollers to cause it to simultaneously engage the middle and either at a time of the end ones of the form rollers, depending on the direction of movement of the same. 110 115

2. An ink distributing attachment for a printing press having three form rollers, and means for moving said rollers as a unit in opposite directions alternately; comprising a distributing roller, frictionally engaging the central one of the form rollers, and means supporting said distributing roller for free turning movement about the axis of said central roller as an axis, whereby with the rotation of said central roller in one direction or the other, the distributing roller will turn to engage one or the other of the endmost of 120 125 130

the form rollers while remaining engaged with the central roller.

3. A structure as in claim 2, with means incorporated with said supporting means to enable the pressure of engagement of the distributing roller with the central form roller to be altered at will.

4. An ink distributing attachment for a printing press having three form rollers, and means for moving said rollers as a unit in opposite directions alternately; comprising a distributing roller, frictionally engaging the central one of the form rollers, a shaft on which said distributing roller is mounted, collars turnably mounted on the axial shaft of the central form roller, and members projecting radially from the collars and supporting the ends of the first named shaft.

5. An ink distributing attachment for a printing press having three form rollers, and means for moving said rollers as a unit in opposite directions alternately; comprising a distributing roller, frictionally engaging the central one of the form rollers, a shaft on which said distributing roller is mounted, collars turnably mounted on the axial shaft of the central form roller, arms projecting radially from the collars, and blocks in which the ends of the first named shaft are supported, mounted on the arms for adjustment lengthwise thereof.

In testimony whereof I affix my signature.
AARON E. KING.
